UNITED STATES PATENT OFFICE.

JOHN WILLIAM DUNGEY, OF PECKHAM, LONDON, ENGLAND.

TELEPHONE RECEIVER.

Application filed January 2, 1926, Serial No. 78,774, and in Great Britain September 12, 1924.

This invention has reference to telephone receivers of the polarized type wherein the shell or rear part of the casing constitutes a permanently magnetized portion of the magnetic system. This system may comprise one or more cores for receiving a coil winding or windings. The shell or rear part has secured thereto an iron diaphragm in the usual manner.

10 According to this invention telephone receivers of the character referred to are of improved construction and enable a comparatively strong and intimate magnetic effect to be obtained in the parts concerned 15 with the result that an improved working efficiency is ensured, the shell or rear part of the casing of the telephone receiver being constituted of magnetizable metal and so magnetized as to comprise two or more independent magnetic systems therein. Each such system may include as a part of its circuit a core which is arranged in connection with the said shell or rear part, and is of opposite polarity to that of an adjacent 20 core of another magnetic system. In this manner a stronger and more intimate magnetic effect is obtained than hitherto in that magnetic circuits exist between the cores of adjacent magnetic systems as well as between each core and the part of the shell or rear part of the casing corresponding therewith. In thus constructing the shell or rear part of the casing and arranging cores in connection therewith the usual iron diaphragm of the telephone receiver is subject to magnetic tension due to each of the magnetic systems produced, the vibrations of the diaphragm upon the passage of electric currents through the coil windings on the 25 cores being correspondingly improved with the number of magnetic systems provided. The cores may be of magnetized metal or of soft iron or constituted of iron wires and may be secured to their respective parts of the shell or rear part of the casing by any suitable means, while the said shell or rear part may be pressed out of sheet metal or may be of cast metal in one piece or constituted of sections. If desired the said shell or rear part may be enclosed in an outer case of metal or material of a suitable character. For varying or adjusting the distance between the ends of the cores and the iron diaphragm, the cores may be adjustably mounted on central portions or pins attached to the shell or rear part or may be fitted with ad-

justable centre pieces, the adjustment of the cores or centre pieces being effected preferably from the outside of the casing. Alternatively, the air gap may be varied as desired by adjustment of the diaphragm, such adjustment being effected by the employment of one or more rings within the earpiece, the ring or rings being preferably disposed between the marginal edge of the said shell or rear part and the diaphragm. The diaphragm is secured or clamped to the said earpiece, or to a cover, trumpet or equivalent part.

In order that the said invention may be clearly understood and readily carried into effect, the same will now be more fully described by way of example with reference to the accompanying drawing, in which:—

Figure 1 is a sectional elevation of a telephone receiver constructed according to this invention.

Figure 2 is a plan view of the telephone receiver shewn in Figure 1, with the earpiece and diaphragm removed.

The shell or rear part *f* of the casing comprises magnet systems respectively existing between the parts *a* *b*, *b* *a'* and *a'* *b'*, the pole extremities of such portions being approximately positioned according to such references and adjacent poles being of opposite polarity, and the parts *a* to *b* and *a'* to *b'* being actually magnetized as required and the parts *b* to *a'* becoming magnetized by induction owing to its proximity to the other magnetic systems. The shell or rear part *f* is of the known bell or cup shape and has disposed within it two cores of soft iron *y* and *z* fitted with coil windings *e* and respectively secured to the shell or rear part *f* by screws or rivets at the points corresponding with the pole extremities *b* and *a'*. The iron diaphragm *c* is arranged in contact with the marginal edges of the shell or rear part *f* and secured in this position beneath the earpiece *d* by a screw threaded ring *g* engaging with the internally screw threaded annular flange of the earpiece. The coil windings *e* are connected with the insulated terminals *h* on the shell or rear part *f*. With this form of construction the iron diaphragm is subject to the magnetic tension exerted by the two poles *y* and *z* of opposite polarity across the gap between the said diaphragm and the poles, magnetic fields being produced between the poles and between the latter and

the respective marginal edges of the shell or rear part *f* of the casing.

What I claim and desire to secure by Letters Patent of the United States is:—

1. In a telephonic receiving instrument, a shell fitted with a diaphragm, the shell consisting of a plurality of permanently magnetized portions spaced from one another by a substantial zone which is not permanently magnetized.

2. In a telephonic receiving instrument, a rear shell fitted with a diaphragm, said rear shell being in one piece and permanently magnetized with a plurality of magnetic portions therein.

3. In a telephonic receiving instrument, an integral cup-shaped rear shell comprising a plurality of permanent magnetic portions therein, and a diaphragm disposed in closed proximity to the edge of the rear shell and subject to the several magnetic portions in the rear shell.

4. In a telephonic receiving instrument, a one piece rear shell having a plurality of permanent magnetic portions therein, a plurality of cores attached to the rear shell, windings on the said cores, and a diaphragm subject to the magnetic portions of the rear shell and the cores.

5. In a telephone receiver, a cup-shaped permanently magnetized rear shell having a plurality of independent magnets therein, peripheral portions of the rear shell being of north and south polarity and intermediate portions of the rear shell also being of north and south polarity, the intermediate portion of north polarity being disposed between the intermediate and peripheral portions of south polarity.

6. A telephone receiver comprising a cup-shaped rear shell magnetized to have a plurality of permanent magnets therein with intermediate portions of north polarity between intermediate and peripheral portions of south polarity, cores attached to the rear shell, windings mounted on the cores, a diaphragm subject to the magnetic flux of the rear shell and cores, and a perforated cap secured to the periphery of the rear shell with the diaphragm between the said periphery and the cap.

7. In a telephonic receiving instrument, a

one piece permanently magnetized rear shell having a plurality of magnets therein oppositely polarized intermediate portions being alternately disposed relatively to oppositely polarized peripheral portions.

8. In a telephonic receiving instrument, a permanently magnetized rear shell having a plurality of magnets therein, portions of one polarity being provided between portions of another polarity.

9. In a telephonic receiving instrument, a permanently magnetized part comprising a plurality of magnets therein and having peripheral portions of north and south polarity and intermediate portions of north and south polarity, the intermediate portions of north polarity being arranged between the peripheral and intermediate portions of south polarity; cores attached to the intermediate portions of north and south polarity; windings on the said cores; and a diaphragm subject to the plurality of magnets and the said cores of opposite polarity.

10. A telephone receiver comprising a shell having more than one permanent magnet therein, cores attached to the shell, windings on the cores forming electromagnets of opposite polarity, a diaphragm subject to the magnetic flux of the shell and electromagnets, and a perforated cap secured to the periphery of the shell with the diaphragm between the said periphery and the cap.

11. A telephone receiver comprising a one piece permanently magnetized cup-shaped part having a plurality of magnets therein, opposite peripheral portions of the said part being of north and south polarity and intermediate portions being of north and south polarity, the intermediate portion of north polarity being arranged between the peripheral portion of south polarity and the intermediate portion of south polarity; cores attached to the intermediate portions of north and south polarity; windings on the said cores; a diaphragm arranged in connection with the periphery of the said part and over the said cores, a perforated cap; and means for securing the cap to the said part over the diaphragm.

JOHN WILLIAM DUNGEY.
